UNITED STATES PATENT OFFICE.

HUBERT BEDDOES, OF CHICAGO, ILLINOIS, ASSIGNOR TO PACIFIC FLUSH TANK COMPANY, OF CHICAGO, ILLINOIS, A CORPORATION OF ILLINOIS.

DOSING-TANK SYSTEM.

Application filed April 9, 1925. Serial No. 21,806.

The dosing tank systems to which my invention relates are commonly employed in connection with filter beds for the treatment of sewage. In distributing the liquid to such filter beds, it is desirable that it be applied thereto intermittently and in large volume of flow during the period of distribution. For this purpose, it has been common to employ two or more tanks in which the liquid 5 accumulates relatively slowly and which are discharged successively or in rotation, the out-flow being in large volume and for a relatively short period of time. The tanks are discharged automatically by means of siphons 10 located therein and connected to a common main or pipe leading to the sprinklers of the filter bed or other point of disposal of the liquid.

Heretofore, in order to prevent the liquid 20 from the siphon of the discharging tank running back up the siphon of a tank in which the liquid is at a lower level and discharging into the latter check valves have been used in the branch connections between the respective siphons and the main. These valves are not entirely satisfactory for the reasons that they tend to become clogged and even when free interfere to a greater or less extent with the flow of liquid. My invention provides a 25 construction in which these valves are dispensed with, a sufficient hydrostatic pressure being at all times maintained in the respective tanks to prevent the back-flow of liquid.

In the accompanying drawings forming a 35 part of this specification, I have disclosed a preferred embodiment of my invention. It will be understood, however, that the specific disclosure is for the purpose of exemplification only and that the scope of the invention 40 is defined in the following claims in which I have endeavored to distinguish it from the prior art without, however, further restricting it.

In the drawings, Figure 1 is a plan view 45 of the preferred embodiment of the invention; Fig. 2 a vertical section thereof on the line 2—2 of Fig. 1; and Figs. 3 and 4 details, partly in elevation and partly in vertical section.

50 I have chosen a two-tank system in connection with which to describe my invention, but it will be understood from the following description that it is applicable to such systems irrespective of the number of tanks involved.

55 The two dosing tanks 8 and 9 are shown as

arranged side by side and separated by the diaphragm or wall 5. The particular arrangement of the tanks is immaterial. All of the tanks are preferably identical in construction and equipment and in the present 60 illustration, they are so shown and therefore except where the inter-action of the tanks is referred to, but one will be described. In the system illustrated, the tanks receive their supply of liquid from a common supply chamber 6. At the entering end, each tank is formed with a well 8 which communicates with the supply chamber by an inverted U-shaped port or air lock 7. Each tank is also provided with a siphon, the bell or shorter 70 leg of which is shown at 9 and the longer leg at 10. From the lower end of each longer or outlet leg of the siphon a branch connection 11 leads to a common main or pipe 12 by which the liquid is conveyed to a filter bed 75 or other point of disposal. The main 12 extends upwardly at 12^a to form a liquid seal for the branches 11.

In the construction shown, the two tanks are discharged alternately and means is provided in each tank for starting the flow 80 through the siphon when the liquid reaches a predetermined level. Such means may be and is shown as the known W-trap comprising a U-pipe, the shorter leg 13 of which communicates with the interior of the siphon bell near its top at 14 and the longer leg 15 of which opens at a point above the maximum level of the liquid in the tank. The trap also 85 comprises a starting bell 16 connected to the 90 bend of the U-pipe by a pipe 17 which intermediate the starting bell and its connection to the U-pipe extends above the maximum liquid level in the tank. The starting bell is located at the proper level to force air into 95 the trap when the liquid in the tank reaches the predetermined maximum level and break the seal of the trap thus permitting the escape of air from the siphon and starting the flow of the latter.

For a purpose which will presently appear the main 12 is provided with a riser 18 connecting to a compression dome or chamber 19. A vent pipe 20 connects the compression chamber with the tanks or either of them and extends downwardly within the dome at 20^a a sufficient distance to form an annular air chamber 40 of sufficient volume or capacity to supply air for the operations to be now described. A pipe 22 extends upwardly from 110

the top of this air chamber and is branched at 23, one of the branches 24 leading to one of the air locks or ports 7 at 25 and the other branch leading to the other port. When 5 either tank discharges the liquid rising in the compression dome, forces the air therefrom through pipe 22 and the proper branch 24 thereof to the air lock of the discharging tank thereby displacing the liquid down- 10 wardly in the said lock or port and closing or locking it against the flow of liquid. In order to provide against the discharge of air into the air lock of the other tank, which is filling at this time, each connection for sup- 15 plying air to the respective air locks is provided with a trap 27 extending into the other or opposite tank. Each trap 27 is provided with a supply pipe 33 as shown in Figure 2 through which the trap fills as the liquid in 20 the tank in which it is located rises and through which the trap empties as the liquid falls. Said supply pipe is liquid sealed by reason of its U-shape to prevent escape of air. At the time that either tank is discharging, 25 obviously the trap therein, which as above stated, controls the supply of air to the port or lock of the other tank is closed by the presence of liquid therein, so that all of the air from the compression chamber is divert- 30 ed to the air lock of the discharging tank, thus cutting off the supply of liquid thereto.

In order to break the air lock at the proper time, each port is provided with an air vent pipe 28 which latter terminates in a trap 29 located in the same dosing tank whose supply of liquid is controlled by said port. In order to break the water seal of the respective traps 29 at the proper time, a bell 30 dips into the compression chamber 19 and is connected to the respective traps 29 by a common pipe 31 and branch pipes 32. When either tank begins to discharge, the liquid rises in pipe 18 and chamber 19, as stated above, and the air compressed in the bell 30 is forced 40 into the trap 29 of the other tank, which at the time is at low level and breaks the seal of the corresponding vent pipe thus permitting the air to exhaust from the air locked port thereof and the liquid to flow to said tank. 50

Obviously, were no provision made to the contrary when one of the pair of tanks discharges, more or less of the liquid therefrom would flow to the other tank of the pair, the liquid in the latter being, at the time, at a lower level. Heretofore, as above stated, valves have been installed in the respective connections to prevent this, but they are subject to the objections pointed out above. Instead of installing valves in the siphon connections, I so design the tanks and their equipment as to maintain in each tank a sufficient hydrostatic head after its discharge to prevent the back-flow of liquid thereto. 65 With this in view each tank is formed with

a relatively deep well *a* about the siphon of relatively small cross section and the bell or short leg *g* of the siphon is of unusual length and dips into said well. A vent 34 is so designed and connected to the bell as to 70 break the siphon and leave in the well a sufficient depth of liquid to prevent flow from the other tank. The vent is provided with a check valve 35 to prevent escape of air from the bell. Theoretically, the equipment of the 75 two tanks being the same, in order to prevent liquid discharging from one tank to another, the lower ends of the bells must be sealed to a depth equal to the distance between the upper end of the long leg of the respective 80 siphons and the maximum liquid level. Practically, due to frictional losses and the like, the depth of seal need not be quite so great.

Assuming one tank has just been discharged and the other tank is full and the 85 liquid standing to the top of the longer legs of the siphons in the respective tanks, when the full tank begins to discharge, the net force tending to cause overflow into the empty tank is obviously the hydrostatic pressure due to the height of liquid above the top of the longer leg of the siphon in the full tank. There is a cushion of air in the bell of the siphon of the empty tank upon which this pressure is exerted, the pressure being 90 resisted by the pressure of the column of liquid remaining in the empty tank above the lower edge of the short leg or bell of the siphon. By so designing the apparatus that the latter column of liquid is never less in 95 height than the column of liquid above the long leg of the siphon in the discharging tank, the transfer of liquid from the latter to the empty tank is avoided.

By locating the siphon of the respective 105 tanks in relatively deep wells of small cross section, a sufficiently deep seal for the purpose may be maintained without substantially diminishing the quantity discharged from the tanks at each operation.

I claim:

1. In a multiple tank liquid distributing system, a plurality of dosing tanks each having a discharge siphon, the siphons being in open connection to a common out-flow pipe, means for starting each siphon when the liquid in the tank in which said siphon is located reaches a predetermined maximum level, means for stopping the siphonic discharge in each tank before the level of the 115 liquid therein drops to a distance above the lower edge of the shorter leg of the siphon less than the distance between the upper edge of the longer leg of the siphon and the maximum liquid level in the other tanks of the system, and means for successively filling said tanks.

2. In a multiple tank liquid distributing system and in combination with a plurality of tanks thereof, discharge siphons for the 120

respective tanks in open connection to a common out-flow pipe, means for venting each siphon to start the flow when the liquid in the tank reaches a predetermined maximum level, 5 means for venting the siphon to stop the siphonic action when the liquid level in the tank is further above the lower edge of the shorter leg of the siphon than the maximum level of the liquid in the tank is above the 10 tops of the longer legs of the siphons, and means for successively filling said tanks.

3. In a multiple tank liquid distributing system, a plurality of tanks, discharge siphons for the respective tanks in open connection to a common outflow pipe, means for starting the flow of liquid through the siphons when the liquid reaches a predetermined level in the tank, a vent for stopping the siphonic flow of liquid from the tank when 20 the column of liquid therein above the lower edge of the shorter leg of the siphon is sufficient to oppose the flow of liquid into said tank from another tank when the liquid in the latter is at the maximum predetermined level, 25 means in said vent to prevent outflow therethrough, and means for successively filling said tanks.

4. In a multiple tank liquid distributing system, a plurality of tanks, discharge siphons for the respective tanks in open connection to a common outflow pipe, means for starting the flow of liquid from each tank when the liquid reaches a predetermined level, 30 means for stopping the flow from each tank at a point to maintain after its discharge a sufficient hydrostatic head above the bottom of the bell of said tank to prevent the flow of

liquid into said tank from a discharging tank, and means for successively filling said tanks.

5. In a multiple tank liquid distributing system, a plurality of dosing tanks each having a discharge siphon, the siphons being connected to a common out-flow pipe, means for starting each siphon when the liquid in the tank in which the siphon is located reaches a predetermined maximum level, and means for stopping the siphon discharge in each tank consisting of a vent pipe connected to the siphon near the top thereof and open to the tank near the lower end of the shorter leg of the siphon and a valve in said vent opening toward the siphon.

6. In a multiple tank liquid distributing system, a plurality of dosing tanks each having a discharge siphon, a common outflow pipe with which said siphons are in open connection, means for starting each siphon when the liquid in the tank in which said siphon is located reaches a predetermined maximum level, means for stopping the siphonic discharge in each tank before the level of the liquid therein drops to a distance above the lower edge of the shorter leg of the siphon less than the distance between the upper edge of the longer leg of the siphon and the maximum liquid level in the other tanks of the system, a passage for supplying each said tank with liquid, an air lock for closing off said passage, means for supplying air to said air lock when the tank with which it is associated is discharging, and means controlled by the discharge of another tank for releasing air from said air lock.

HUBERT BEDDOES.

CERTIFICATE OF CORRECTION.

Patent No. 1,715,185.

Granted May 28, 1929, to

HUBERT BEDDOES.

It is hereby certified that error appears in the printed specification of the above numbered patent requiring correction as follows: Page 3, line 9, after the word "the" second occurrence, insert the word "other", and same line, for the word "tank" read "tanks"; and that the said Letters Patent should be read with these corrections therein that the same may conform to the record of the case in the Patent Office.

Signed and sealed this 30th day of July, A. D. 1929.

M. J. Moore,
Acting Commissioner of Patents.
